DURELL O. PEASE, OF HAMPTON, MASSACHUSETTS.

THREAD-BOARD FOR SPINNING-MACHINES.

1,118,226.

Specification of Letters Patent. Patented Nov. 24, 1914.

Application filed February 8, 1913. Serial No. 747,978.

To all whom it may concern:

Be it known that I, DURELL O. PEASE, a citizen of the United States of America, and resident of Hampden, in the county of 5 Hampden and State of Massachusetts, have invented certain new and useful Improvements in Thread-Boards for Spinning-Machines, of which the following is a full, clear, and exact description.

10 The object is to provide an improved "thread board," or a series of guides for spinning frames which is more particularly adapted to those frames designed and built for the spinning of what is known as "condensed rovings" or rovings made by the 15 woolen process.

20 The form of thread guide most commonly employed is defective for this class of spinning, for what is known as the "pig-tail" 25 or yarn guide stands out from the back-board and leaves an open space between the adjacent guides.

25 The cause of the above named defect lies in the fact that when a broken end occurs in the spinning of this kind of roving, the 30 end extending from the bite of the delivery roller tends to come straight down and is almost certain to fall or get caught in some one of the immediately adjacent ends to 35 cause snarls that will break many more ends before the attendant can get them pieced up; but by providing a thread board as here shown and described, no broken end can get past the location of the thread board 40 to cause the aforesaid trouble.

45 And in the present device means are provided with which the yarn or thread may be engaged and by which it will be retained in the operation of piecing, it being understood that in this class of spinning the ends on the yarn have to be untwisted and made soft in order to be "pieced" or spliced, and so, when a piecing is to be performed, the 50 yarn end below the thread board and toward 55 the spindle is upwardly drawn to a position above the thread board and caused to have an engagement with the latter while the portion coming from the delivery rolls is adjoined therewith.

50 A further improvement consists in the provision of parts or sections of the thread board which are operative to guide and retain the yarn over the center of the spindle,—the same being adjustable so as to be 55 properly positioned even although the rail in a comparatively long spinning machine

may be more or less undulating or untrue as regards the line of its forward edge,— and such adjustable parts or sections moreover are removable so as to be replaced, after 60 having become badly worn, by new and perfect ones.

The invention is described in conjunction with the accompanying drawings and is set forth in the claims.

65 In the drawings:—Figure 1 is a plan view of a comparatively short portion of a thread board constructed in accordance with the present improvements. Fig. 2 is a sectional elevation of a sufficient portion of a spinning frame to show the position of the thread board with relation to the delivery rolls and spindles. Fig. 3 is a cross sectional view on line 3—3, Fig. 1.

70 In the drawings, A represents the main 75 longitudinally ranging supporting rail of which the thinner and narrower supplemental rail section A² is the same as an integral part; and to the supporting rail a plurality of blocks B are connected by hinges b.

75 Each block B is made with a shallow forwardly opening channel d within its top; and each so channeled block receives therein the shank portion f of an L-shaped steel plate, the flange portion g of such plate being 80 downwardly extended forward of the edge of the supporting bar.

85 Upon each block is another plate D which is detachably secured in clamping confinement against the shank of the L-shaped plate 90 by bolts h h.

95 The thickness of each of the L-shaped plates is slightly greater than the depth of the channels so that the top plate D, when the bolts are tightened by the nuts has a firm binding engagement against the portion of the L-shaped plate which is partially pocketed in the channel.

100 The forward depending flange like member of each of the confined plates is to be adjusted in position coincident with the axis of the spindle w which has the usual location therebelow, and to which spindle the thread or yarn is brought from the delivery rolls w w, guided through the thread board.

105 Each clamping plate D secured above the L-shaped plates and extended considerably forwardly beyond them, is provided with a recess i which extends from its forward edge rearwardly more or less beyond the 110 location of the depending flange like portion g of the other plate.

Each of these recesses is widened between its forward and rear ends forming a pair of shoulders *j j* as shown, and such recesses forwardly from the widened shoulder forming places are forwardly divergent to permit of the quick and easy entrance of the yarn to its place of guidance or to its engagement with either one of the shoulders at the time of "piecing up."

10 The support blocks in each of which one, or more than one, set of the L-shaped, and clamping, plates are provided by being hinged to the main support rail may be swung back for dosing as usual in this general class of appliances; and by making and combining the parts as described, the L-shaped plates are individually adjustable so as to be brought with their flanges all in alinement even although the supporting rail 20 may be considerably warped or out of true.

The upper plates, the transverse edges of which are contiguous, close the spaces between the guides and form a guard or barrier below which a broken yarn cannot pass 25 to become entangled with and cause breakage of other running yards.

When a yarn or thread becomes severed and it is required to piece the same, the portion or broken "end" below the thread board 30 and toward the spindle is seized, carried into the recess *i* in the upper plate which has a shelf like extension forward of its supporting member, and by a sidewise movement is brought to engagement with a shoulder *j* at either side of the recess. This stays the lower yarn end, it being retained 35 in its shoulder engaged position with one hand while a splice or piecing with the other end coming from the delivery roll is being 40 accomplished in the usual manner.

Although the L-shaped plates are made of hardened steel, they will under protracted use become grooved at their fronts so as to be impaired in efficiency; and their replacement by new ones may be readily effected by simply loosening the bolts which 45 confine the upper clamping plate and after the engagement and adjustment of a new L-shaped plate in the shallow channel therefore, the bolts will be again tightened.

The making of the mouth portions of the

recesses *i* forwardly divergent and having the corners of the plate at the opposite margins of the recessed mouths rounded conduces to the facility of introduction of the 55 yarn to its running line of guidance and prevents any liability of the same becoming caught or broken in any stage of a piecing up operation.

I claim:—

1. In a thread board for spinning machines, the combination with a supporting member having a forwardly opening channel within its top, of an L-shaped plate having the shank portion thereof disposed in 65 said channel and having the flange like portion thereof downwardly extended forward of the edge of the supporting member, and another plate detachably secured on the top of the supporting member having a clamping confinement on said plate, and provided with a recess extending from its forward edge rearwardly beyond the location of the forward flange like portion of the L-shaped plate. 70

2. In a thread board for a spinning machine, the combination with a main supporting rail, of a plurality of blocks hinge connected on the front of the rail and each having a forwardly opening channel within its 80 top, a series of L-shaped plates each having the shank portion thereof disposed in said channel and having the flange like portion thereof downwardly extended forward of the edge of the supporting block and a further series of plates detachably secured on the tops of said blocks, having clamping confinement on said plates and each provided with a recess extending from its forward edge rearwardly beyond the location 85 of the forward flange like portion of the L-shaped plate clamped thereby, such recess being widened to form a shoulder at one side thereof between its forward and rear end. 90

Signed by me in presence of two subscribing witnesses.

DURELL O. PEASE.
